UNITED STATES PATENT OFFICE.

GEORGE WILLIAM LANE, OF PROVIDENCE, RHODE ISLAND.

AIR-INTAKE AND PRIMING DEVICE.

Application filed June 14, 1921. Serial No. 477,492.

To all whom it may concern:

Be it known that I, GEORGE W. LANE, a citizen of the United States, residing at Providence, in the county of Providence and State of Rhode Island, have invented new and useful Improvements in Air-Intake and Priming Devices, of which the following is a specification.

This invention relates to an air intake and 10 priming device for internal combustion engines, and the object is to provide a device which may be carried on the steering column or dash-board of a motor car, being connected by tubing with the intake manifold, and 15 being adapted for use, when provided with a priming fluid, as a priming device, and capable of use at other times as an auxiliary air intake.

A further object is to provide, in connection 20 with a suitable tubular element between the dash-board and intake manifold, a casing to be mounted on said board, and an element constituting a valve member cooperating with the casing and adapted to control 25 the admission of fuel to the engine, or the admission of air, as the case may be.

A still further object is to provide a particular type of valve member, whereby the purposes specified may be realized.

30 A still further object is to provide a particular form of connection between the intake manifold and the tubular element connected with the casing on the dash-board.

In the drawings, Figure 1 shows the device 35 in side elevation, and connected with an intake manifold; Figure 2 is a front elevation of the device independent of its connections; Figure 3 is a vertical section; Figure 4 is a vertical section at an angle of 90 degrees 40 from that of Figure 3; Figure 5 is a perspective view of the valve member; Figure 6 shows an elbow for connecting the device with an intake manifold.

With the foregoing and other objects in 45 view, the invention consists in the novel construction and arrangement of elements described and claimed, it being understood that modifications may be made within the scope of the claims, without departing from 50 the spirit of the invention.

The intake manifold 10 has connected therewith an elbow 11 provided with the threaded portions 12 and 13, one of these threaded portions being connected by a 55 coupling 14 with the tubular element 15, and the latter extending to the connection 15' in

the casing 16. The port through this connection is designated 17.

A slot 18 is provided in one side of the casing, and accommodates a handle 19 of the 60 valve member 20. This valve member is of disk form having a flange 21, cutaway as shown at 22 to provide a tapered portion 23 and a shoulder 24, the tapered portion permitting of partial closing of the port 17 65 prior to fully closing that opening.

The disk or valve member is further provided with apertures 25, and when the engine is running at a considerable speed, and it is desired to admit more air, this valve 70 may be employed for that purpose, and may further be employed for admitting air for braking purposes when the car is proceeding down grade with the throttle closed.

The casing is provided with a central boss 75 26 receiving a screw 27, the end of which passes into the valve member. A coiled spring 28 surrounds the boss and bears against the inner surface of the valve member, producing sufficient friction to retain 80 the valve in a given position.

Priming fluid may be introduced when desired through the ports shown, and preferably through ports 30 and 31, these ports being in registration when the handle 19 is 85 in the position shown in Figure 3 (port 17 then being open).

Connected with the elbow and projecting into the manifold is a tubular element 34 having longitudinal slots 35 therein, permitting of the passage of air into the manifold, as through a flat nozzle or a series of such nozzles. The end 36 is also open.

It will be understood that the auxiliary air supply is intended to economize fuel and 95 to produce a mixture giving the best results under given conditions.

What is claimed is:

1. In an auxiliary air intake device, a casing having a port in the wall thereof and 100 also having a slot in said wall, a valve member of disk form having apertures therein and having a flange provided with a cutaway portion, and a handle for said valve projecting through the slot in the casing. 105

2. An auxiliary air intake device, comprising a casing having a port in the wall thereof adapted to place the casing in communication with an intake manifold, the casing also having a segmental slot in one 110 wall thereof, a valve member of disk form having apertures therein and having a

flange provided with a cutaway portion formed with a tapered wall and a shoulder, the tapered wall cooperating with the aforesaid port, and an operating device connected 5 with the valve member and passing through the aforesaid slot.

3. An auxiliary air intake device, comprising a casing having an inlet and an outlet port and having a slot in one wall, a 10 valve member of disk form mounted in the

casing and provided with apertures, said valve member also being provided with an inlet port and with an outlet port one of which has an inclined wall extending in a direction circumferentially of the valve, and 15 an operating device connected with the valve member and projecting through the aforesaid slot.

In testimony whereof I affix my signature.
GEORGE WILLIAM LANE.
